UNITED STATES PATENT OFFICE.

JOSEPH TOMSANY, OF WHEELING, WEST VIRGINIA.

ROPE-GUARD FOR BORING-RIGS.

1,237,414.

Specification of Letters Patent. Patented Aug. 21, 1917.

Application filed April 30, 1917. Serial No. 165,409.

To all whom it may concern:

Be it known that I, JOSEPH TOMSANY, a citizen of the United States, residing at Wheeling, in the county of Ohio and State 5 of West Virginia, have invented certain new and useful Improvements in Rope-Guards for Boring-Rigs, of which the following is a specification, reference being had to the accompanying drawings.

10 This invention relates to certain improvements in rope guards for boring rigs, and it is an object of the invention to provide novel and improved means for holding the rope during a drilling operation out of contact with the upper edge of the pipe or casing, so that the life of the rope is materially prolonged.

15 It is also an object of the invention to provide a novel and improved rope guard which 20 serves to maintain the portion of the rope immediately adjacent and above the top of the pipe or casing straight when the drill strikes bottom.

25 The invention also has for an object to provide a novel and improved rope guard which may be readily and conveniently rendered inoperative, especially during a bailing operation.

30 The invention consists in the details of construction and in the combination and arrangement of the several parts of my improved rope guard whereby certain important advantages are attained and the device is rendered simpler, less expensive and otherwise 35 more convenient and advantageous for use, all as will be hereinafter more fully set forth.

The novel features of the invention will hereinafter be definitely claimed.

40 In order that my invention may be the better understood, I will now proceed to describe the same with reference to the accompanying drawings; wherein—

45 Figure 1 is a view in elevation illustrating a rope guard constructed in accordance with an embodiment of my invention in applied position, certain parts being indicated by dotted lines in a second position.

50 Fig. 2 is a fragmentary view, partly in section and partly in elevation, illustrating certain features of the invention as herein disclosed; and

55 Fig. 3 is a sectional view taken substantially on the line 3—3 of Fig. 1 and looking in the direction of the arrow.

As disclosed in the accompanying draw-

ings; C denotes the upper end portion of a pipe or casing such as is generally employed in a well boring operation, and the upper or outer extremity of said pipe has 60 affixed thereto a surrounding collar or sleeve 1.

A denotes an anchoring member comprising two hingedly connected sections 2, adapted to straddle or embrace the pipe or casing 65 C below and preferably immediately adjacent the collar or sleeve 1. The free ends of the sections 2 have coacting therewith a clamping means 3, whereby the anchoring member A is effectively held in applied position upon the pipe or casing C, yet capable of ready removal therefrom when required.

70 Each of the sections 2 midway its length is provided with the outstanding spaced 75 wings 4 arranged transversely of the section 2, and between which is pivotally engaged as at 5, an upstanding arm 6 of predetermined length. The upper or free end portion of the arm 6 is provided with inwardly directed spaced wings 7, having positioned therebetween and rotatably supported thereby a grooved roller or pulley 8.

75 When the arms 6 are at the limit of their upward swinging movement the rollers or 80 pulleys 8 engage with the rope R which passes therebetween. The rope R is adapted to coact in a conventional manner with a drill (not shown), and it will be at once 85 self-evident that the rope R below the rollers 90 8 will be maintained straight, which is of particular import when the drill strikes bottom, as the rope is thereby prevented 95 from slackening as indicated by dotted lines at a. The slackening or buckling of the rope 100 results in the rope contacting with and being drawn over the upper or outer edge of the pipe or casing C and thereby becoming materially worn, whereas it will be at once perceived that with the use of my improved gear this material disadvantage is avoided 105 and the life of the rope R materially prolonged.

110 Threaded through each of the arms 6 at a predetermined spaced relation relative to the pivot 5 thereof is a screw 9, which serves as an endwise adjustable stop member adapted to contact with the upper or outer end portion of the pipe or casing C, or more particularly the collar or sleeve 1, so that the limit of the inward swinging movement of the arm 6 may be regulated in accord-

ance with the requirements or necessities of practice.

Each of the arms 6 at its pivoted end is provided with an outwardly inclined tail 10, having its free extremity angular in cross section, with one face oppositely beveled as indicated at 11, and with which coacts the conical end 12 of a screw 14 or the like, disposed through and carried by an end portion of a flat spring 15, held at a point intermediate its length to the outer face of one of the wings 4, by a pivot member 5, herein disclosed as a headed bolt having coacting therewith a clamping or retaining nut 16. The coaction between the screw 14 and the opposite bevels 11 of the tail 10 serve to maintain the arm 6 at the limit of its inward movement, or at the limit of its outward movement as indicated by dotted lines in Fig. 1. The outer position or adjustment of the arm 6 is desirable during a bailing operation.

Each of the springs 15 is held against swinging movement about the pivot member 5 by the finger or screw 17 disposed through the end portion of the spring remote from the screw 14, and which seats within a recess 18 formed in the upper edge of the adjacent wing 4.

From the foregoing description, it is thought to be obvious that a rope guard constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as herein-after claimed.

I claim:

1. A rope guard comprising a member adapted to be affixed to a pipe or casing, arms pivotally engaged with said member, the outer portions of said arms being adapted for engaging with the rope, and means for holding the arms at the limits of their movements in opposite directions.

2. A rope guard comprising a member adapted to be affixed to a pipe or casing, arms pivotally engaged with said member, the outer portions of said arms being adapted for engaging with the rope, means for holding the arms at the limits of their move-

ments in opposite directions, and adjustable means carried by the arms for limiting the movement thereof in one direction.

3. A rope guard comprising a member adapted to be affixed to a pipe or casing, arms pivotally engaged with said member, the outer portions of said arms being adapted for engaging with the rope, means for holding the arms at the limits of their movements in opposite directions, and adjustable means carried by the arms for limiting the movement thereof toward the casing.

4. A rope guard comprising a member adapted to be affixed to a pipe or casing, arms pivotally engaged with said member, the outer portions of said arms being adapted for engaging with the rope, means for holding the arms at the limits of their movements in opposite directions, each of said arms being provided with a tail, and means coacting with the tail for locking the arm at the limit of its movement in either direction.

5. A rope guard comprising a member adapted to be affixed to a pipe or casing, arms pivotally engaged with said member, the outer portions of said arms being adapted for engaging with the rope, means for holding the arms at the limits of their movements in opposite directions, each of said arms being provided with a tail, and a yieldingly supported member coacting with the tail for locking the member at the limit of its movement in either direction.

6. A rope guard comprising a member adapted to be affixed to a pipe or casing, arms pivotally engaged with said member, the outer portions of said arms being adapted for engaging with the rope, and means for locking the arms at their limit of movement in one direction.

7. A rope guard comprising an anchoring member, opposed arms pivotally engaged therewith, means for locking the arms when at the limit of their movement one toward the other, and pulleys carried by the outer end portions of the arms between which the rope is adapted to pass.

8. A rope guard comprising an anchoring member, arms pivotally engaged therewith, the outer portions of said arms being adapted for engaging with the rope, and means for locking the arms at their limit of movement in one direction.

In testimony whereof I hereunto affix my signature in the presence of two witnesses.

JOSEPH TOMSANY.
